The ornamental design for an LED light fixture, as shown and described.

DESCRIPTION

FIG. 1 is a perspective view of a first embodiment of the LED light fixture, showing the new design;

FIG. 2 is a top plan view of the first embodiment of the LED light fixture;

FIG. 3 is a bottom plan view of the first embodiment of the LED light fixture;

FIG. 4 is a side elevation of the first embodiment of the LED light fixture, an opposing side elevation of the LED light fixture being identical;

FIG. 5 is an end elevation of the first embodiment of the LED light fixture, an opposing end elevation of the LED light fixture being identical;

FIG. 6 is a perspective view of a second embodiment of the LED light fixture, showing the new design;

FIG. 7 is a top plan view of the second embodiment of the LED light fixture;

FIG. 8 is a bottom plan view of the second embodiment of the LED light fixture;

FIG. 9 is a side elevation of the second embodiment of the LED light fixture, an opposing side elevation of the LED light fixture being identical;

FIG. 10 is an end elevation of the second embodiment of the LED light fixture, an opposing end elevation of the LED light fixture being identical;

FIG. 11 is a perspective view of a third embodiment of the LED light fixture, showing the new design;

FIG. 12 is a top plan view of the third embodiment of the LED light fixture;

FIG. 13 is a bottom plan view of the third embodiment of the LED light fixture;

FIG. 14 is a side elevation of the third embodiment of the LED light fixture, an opposing side elevation of the LED light fixture being identical; and,

FIG. 15 is an end elevation of the third embodiment of the LED light fixture, an opposing end elevation of the LED light fixture being identical.

The broken lines shown in the drawings illustrate environmental structures that form no part of the claimed design.
